UNITED STATES PATENT OFFICE.

CHESTER T. ALLCUTT, OF PITTSBURGH, PENNSYLVANIA, ASSIGNOR TO WESTINGHOUSE ELECTRIC & MANUFACTURING COMPANY, A CORPORATION OF PENNSYLVANIA.

WIRELESS AMPLIFIER.

Application filed December 31, 1918. Serial No. 269,130.

To all whom it may concern.

Be it known that I, CHESTER T. ALLCUTT, a citizen of the United States, and a resident of Pittsburgh, in the county of Allegheny and State of Pennsylvania, have invented a new and useful Improvement in Wireless Amplifiers, of which the following is a specification.

My invention relates to vacuum apparatus of the type commonly employed for the amplification of impulses in the transmission of intelligence, having particular reference to that type of apparatus wherein the flow of charged bodies from a hot electrode to a cold electrode is under the control of a grid electrode charged in accordance with the incoming impulses, the charged bodies being permitted to traverse said grid electrode to a greater or less degree, dependent upon the potential thereof.

My invention has for its object to provide apparatus of the character designated that shall be simple and reliable in operation and more sensitive than the forms of apparatus commonly employed hitherto for this purpose.

Fig. 1 of the accompanying drawing is a partially sectional perspective view of a vacuum-tube, together with its associated circuits and apparatus illustrating a preferred form of my invention; and Fig. 2 is a partially sectional side view of the apparatus shown in Fig. 1.

Amplifiers are well known wherein a continuous electron stream is emitted from a hot cathode within an evacuated space, and the number of electrons permitted to impinge upon the anode or cold-electrode is determined by an intervening grid member connected to the antenna of the line wire so as to be energized in accordance with the incoming impulses. With apparatus of this type, as usually constructed in the past, the electrons left the hot cathode and traveled at high velocity through the grid to the cold plate. Because of this high velocity, it has been necessary for the grid to acquire a pronounced change in potential and electrostatic influence before being enabled to appreciably change the number of electrons reaching the cold plate.

In accordance with my invention, I provide means whereby the electrons are emitted from the hot cathode and are then brought down to a relatively low velocity before be-

ing acted upon by the grid, thus permitting the grid to produce a much more marked change in the number of electrons passing, with a given change in the potential of the grid.

Referring to the drawing for a more detailed understanding of my invention, I show an evacuated container at 1 in which are mounted two plate electrodes 2 and 3, a hot-wire cathode 4, and a grid electrode 5. The hot cathode 4 preferably lies substantially in the plane of the electrode 3, as shown, and the electrode 2 is parallel to the common plane of the electrodes 3 and 4 and spaced some distance therefrom. The grid 5 is mounted between the plate electrodes 2 and 3.

A magnet 6 is disposed outside the container in such manner as to produce a magnetic field, the lines of which are substantially parallel to the plate electrodes 2 and 3 or transverse to an electron path between these electrodes.

The electrodes 2 and 4 are connected, respectively, to the positive and negative terminals of a battery 7 so as to maintain a fixed unidirectional difference of potential therebetween, and the electrode 4 is further connected across a small current source in order to maintain this electrode at incandescence. A receiving device 8, such, for example, as a telephone receiver only, is connected between the electrodes 3 and 4 but any other well known form of receiver or receiver circuit can be employed. The receiving circuit from an antenna 9 is connected between the electrodes 3 and 5.

Having thus described the arrangement of a system embodying my invention, the operation thereof is as follows: Upon heating the electrode 4 by the passage of electric current therethrough, a stream of electrons is generated and flows towards the plate 2 because of the difference of potential between the electrodes 2 and 4. The effect of the magnetic field produced by the magnet 6, however, is to cause the path of the electrons to bend around in cycloidal shape to such an extent that the electrons are forced to travel away from the plate 2, as indicated by the dotted lines. The electrostatic attraction of the plate 2 upon the electrons moving therefrom tends to radically lower the velocity of the electrons so that, when they reach the grid 6, they are moving at a rela-

tively low velocity, passing through the grid 5 and impinging upon the electrode plate 3 to produce current flow through the receiving device 8. The effect of the incoming 5 impulses of the antenna 9 is to continuously alter the potential of the grid 5, and slight alterations in the potential thereof produce pronounced changes in the number of relatively low-velocity electrons attempting to 10 pass therethrough, thus causing the receiving apparatus to be extremely sensitive to changes in the grid potential.

The electrostatic influence of the electrode 2 is unaffected by whether this electrode is 15 within or without the tube 1.

My invention is illustrated in connection with a wireless system wherein it may further be employed for generating and amplifying but I equally contemplate its use in 20 connection with line-wire systems, as for a telephone amplifier.

While I have shown my invention in its preferred form, it will be obvious to those skilled in the art that it is susceptible of various minor changes and modifications without departing from the spirit thereof and I desire, therefore, that only such limitations shall be placed thereupon as are imposed by the prior art or are specifically set forth in 30 the appended claims.

I claim as my invention:

1. In a vacuum-type amplifier, a hot cathode for the production of a stream of electrons, an auxiliary anode disposed adjacent 35 thereto, means for maintaining a difference of potential between said electrodes, whereby substantially all the electrons emitted by said cathode are drawn toward said anode, means producing a magnetic field transverse 40 to the path of said electrons, whereby they are forced to assume a cycloidal path and eventually travel away from said anode, with attendant diminution of velocity, a grid electrode disposed to intercept the electron path at this point of relatively low 45 velocity, a main anode disposed beyond said grid, means responsive to variations in current flow between said cathode and said main anode, and means for varying the potential of said grid electrode.

2. A method of increasing the efficiency of vacuum-tube amplifiers comprising the step of initiating the movement of an electronic stream in a given direction and then causing 55 the same electronic stream to move in substantially the opposite direction.

3. In combination with means for producing electronic emission in a given direction, of means for causing such emission to move 60 in substantially the opposite direction.

4. In combination with means for producing electronic emission, a plate co-operative

with said means for the impingement of emitted electrons, further means for giving to said electrons a velocity component away 65 from said plate in a direction substantially normal thereto and still further means for giving to said electrons a velocity component toward said plate.

5. In combination with means for producing a stream of electrified bodies, a plate co-operating with said means for taking up the charges of said electrified bodies, means for giving to said charged bodies a velocity 70 away from said plate in a direction substantially normal thereto, and further means for thereafter giving to said bodies a velocity 75 toward said plate.

6. A method of increasing the efficiency of vacuum-tube amplifiers comprising the step 80 of giving to the emission an accelerating gradient in the direction of the current flow toward the receiving plate and then reversing the gradient in the direction of such current flow to such a degree that in the neighborhood of a grid in the path of such emission stream the velocity shall be substantially that of the original stream.

7. In combination with the filament, grid, and plate of a vacuum-tube amplifier, means 85 for increasing the velocity of the stream flow of electrons away from the grid and plate in a direction substantially normal thereto, and further means for diminishing 90 such velocity and directing the stream flow 95 toward the grid and plate.

8. In combination with the cathode of a vacuum-tube amplifier, an electrode opposite said cathode, a second electrode in a plane substantially parallel to said cathode, and a 100 grid between said two electrodes.

9. In combination with the filament and plate of a vacuum-tube amplifier, means for increasing the velocity of the stream flow of electrons away from the plate, further 105 means for diminishing such velocity and directing the stream flow toward the plate, and still further means for controlling the electron flow between said filament and plate.

10. In combination with the filament, grid, and plate of a vacuum-tube amplifier, means for increasing the velocity of the stream flow of electrons away from the grid and plate, further means for diminishing such 115 velocity and directing the stream flow toward the grid and plate, and still further means for setting up a magnetic field substantially parallel to the planes of said electrodes.

In testimony whereof, I have hereunto 120 subscribed my name this 12th day of Dec. 1918.

CHESTER T. ALLCUTT.
